8 Claims. (Cl. 233—27)

The invention relates to a cover arrangement for a centrifuge having an upwardly open drum, in particular for an industrial centrifuge in which to empty the drum, the drum wall is liftable in relation to the drum bottom so that the centrifuged material can slide off the drum bottom and be carried away downwardly.

The known cover arrangements for centrifuges having upwardly open drums consist of a flap cover hinged to the outer casing of the centrifuge, which can be locked to the outer casing when closed. These cover arrangements have the disadvantages that they need considerable room for opening the centrifuge and that the centrifuge cannot be filled from the side to which the flap is hinged.

A purpose of the invention is to provide a cover arrangement for centrifuges in which the disadvantages of the known cover arrangement are mitigated and which also permit reliable closing of the drum chamber as well as easy, rapid and clean filling with material to be centrifuged.

According to the invention a plurality of flaps above the drum are pivoted on horizontal axes lying substantially in the same plane around the axis of rotation of the drum, to the outer casing of the centrifuge, the flaps being of such shape that in horizontal position their side margins overlap and they cover the drum chamber while when in a downwardly inclined position, preferably at an angle to the horizontal of from 40 to 60°, they form a filling funnel for the drum, each flap except the lowermost being engaged from below by a neighbouring flap and the lowermost flap being adjustable about its pivotal axis by an adjustable device.

In a centrifuge according to the invention the drum chamber is closed by the lowermost flap being swung up into a horizontal position by the adjusting device, the other flaps thereby being lifted into the horizontal position. In their lower positions in which the flaps preferably abut against limiting stops, they form a large filling funnel.

In a preferred embodiment of the invention the outer casing of the centrifuge has a square outline at least at its upper edge and the flaps are of trapezium shape, the longest edges of which are equal to the length of the sides of the square opening to which they are respectively hinged.

With this construction the whole cross section of the outer casing is utilised as a charging opening for the material to be centrifuged. The straight side walls of the outer casing of the centrifuge and the large charging opening make it possible to supply the centrifuge in a particularly simple manner by means of band, vibrating or similar conveyors. The covering flaps are advantageously brought into the closed position by a hydraulic or pneumatic cylinder which actuates the lowermost flap. As long as pressure fluid is supplied to the cylinder the flaps are held in the horizontal, closed position. When the centrifuge drum is stationary the cylinder control is operated to release the pressure fluid and the cover flaps sink into the funnel-forming position, for example, under their own weight. The downward swing of the flaps is advantageously limited by rubber buffer stops.

Further features of the invention will appear from the following description of an example of embodiment of

2

a centrifuge according to the invention with reference to the accompanying drawings.

FIG. 1 is a side view partly in section of the centrifuge with the cover flaps in the funnel-forming position.

FIG. 2 is a perspective view of the upper part of the centrifuge with the flaps almost closed.

The centrifuge drum consisting of a conical drum bottom 9 and a drum wall 12 which can be lifted above the bottom, is carried and driven by the hollow shaft 2 of an electric motor 3. The motor 3 is elastically mounted by the aid of a segment piece 4, a flange 5 and a stem 6 secured therein which is set in known manner in rubber rings which are held in the pedestal 7 of the centrifuge and held compressed by a clamping flange 8. The drum wall 12 is connected by radial spokes 13 with a central hub 14 surrounding a hydraulic cylinder 40 and serving to guide the drum wall 12 axially. Inside the cylinder 40 is a piston 41 which when the cylinder is supplied with pressure fluid, presses through a piston rod 42 against an end closure 43 of the hub 14 so lifting the drum wall 12 and opening the drum. The pressure fluid reaches the cylinder 40 through the hollow shaft 2.

Liquid separated by the action of the centrifuge is led over a thrower ring 18 on the drum wall, and a receiving surface 20 secured to the outer casing 21 of the centrifuge, to a discharge tube 22. Inclined guide walls 24 are arranged below the drum bottom 9 which guide the centrifuged material to the discharge openings 25.

The cross section of the outer casing 21 is square at least 30 in its upper region. To the upper edges of the casing 21 four trapezium shaped flaps 80, 81, 82, 83 of steel sheet are pivoted on horizontal axes 84, 85, 86, 87. Each flap is attached at its longest side corresponding to the length of the side walls of the casing 21 by two hinges 88 to the casing 21. As FIG. 1 shows the flaps inclined downwardly to the horizontal at about 50° form a filling funnel of wide cross section. In this open position the flaps abut against yielding stops in the form of rubber buffers 89 attached to the interior of the casing 21. The two side margins of the flaps 82 are respectively engaged from below by one side margin each of the flaps 81 and 83, while the other side margins of the flaps 81 and 83 are engaged from below by the side margins of the lowermost flap 80.

45 After charging of the drum 9, 12 the lowermost flap 80 is swung up into the horizontal position through a lever arm 90 secured to the flap and projecting over and out of the casing 21 by the aid of a hydraulic cylinder 91 engaging the lever arm 90. During this movement the flap 80 carries with it the flaps 81 and 83 resting on it and these in turn carry with them the flap 82 so that the drum space 92 is closed. As long as the piston in the cylinder 91 is under pressure the flaps 80 to 83 are held in the closed position. When the centrifuge drum 40 is at rest the cylinder 91 is controlled preferably automatically to release the pressure fluid and the flaps sink into funnel-forming position.

50 The flaps 80 to 83 can be so arranged that in the funnel-forming position and with the drum itself closed their lower edges are at only a short distance above the upper edge the drum wall 12 because when the drum is opened that is the drum wall 12 is raised, the flaps 80 to 82 can be carried upwardly with it.

55 The two hinge axes 85 and 87 parallel with one another are arranged at the same level, while the hinge axis 86 of the flap 82 is arranged above by the thickness of this flap and the hinge axis 84 of the lowermost flap 80 is arranged below by the thickness of the flap. The upper edges of the four side walls of the casing 21 differ in 60 height by the same amounts.

65 As FIG. 2 shows the driving motor 3 can be controlled through a switch 93 mounted on the outside of the

casing 21 this switch being actuated by a tongue 94 fixed to the flap 80 and projecting out of and over the casing, when the flap 80 and the other flaps are in the closed position.

What I claim is:

1. A centrifuge comprising a rotatable drum open at the top and having a bottom wall and a peripheral wall, said drum being mounted on a vertical drive shaft for rotation therewith, a drive motor coupled to said shaft, means for vertically separating said bottom wall and said peripheral wall to permit discharge of the drum contents between the lower edge of said peripheral wall and said bottom wall, a housing surrounding said drum and having a sidewall extending above said peripheral wall, and a combined cover and filling funnel for said drum, said cover comprising a plurality of radially disposed flaps, each flap being hingedly mounted along an outer edge on the upper edge of said sidewall and projecting radially inwardly of said sidewall, said flaps when in horizontal position with adjacent side edges overlapping providing a substantially closed cover for said drum, said flaps being movable from said horizontal position downwardly to an inclined position of the order of forty to sixty degrees to form a filling funnel for said drum, the side edges of one flap underlying the side edges of adjacent flaps, and means connected to said one flap for moving the same between horizontal and inclined position, said adjacent flaps by reason of the overlapping engagement with said one flap moving therewith.

2. A centrifuge as defined in claim 1 in which yieldable buffers are provided for engaging said flaps to limit the downward pivotal movement thereof to said inclined position.

3. A centrifuge as defined in claim 1 in which at least the upper portion of said housing is of square cross-section and in which said cover comprises four flaps, each flap being of trapezium shape with the longer edge being hingedly mounted on the adjacent upper edge of said housing with the length of said longer edge being equal to the length of said last named adjacent upper edge.

4. A centrifuge as defined in claim 3 in which the two flaps adjacent one flap are hingedly mounted above said one flap a distance equal to the thickness of said one flap, the fourth flap being hingedly mounted above said two flaps a distance equal to the thickness of said two flaps.

5. A centrifuge as defined in claim 1 in which said means for moving said one flap includes a lever arm secured to said one flap and projecting outwardly over the adjacent upper edge of said housing, and power actuated means connected to said lever arm for moving said one flap.

6. A centrifuge as defined in claim 5 in which said

power actuated means comprises a fluid pressure operated cylinder.

7. A centrifuge as defined in claim 1 in which a tongue is mounted on said one flap, said tongue projecting outwardly over the adjacent upper edge of said housing, and a control switch mounted on said housing in the path of movement of said tongue, said switch being connected to said motor, whereby when said one flap is in horizontal position said switch will be actuated to energize said motor.

8. A centrifuge comprising a rotatable drum open at the top and having a bottom wall fixed to a vertical drive shaft and a vertically movable peripheral wall, a drive motor coupled to said shaft, said peripheral wall engaging said bottom wall when in operating position and movable upwardly to permit discharge of the drum contents between the lower edge of said peripheral wall and said bottom wall, a housing surrounding said drum and having a sidewall extending above said peripheral wall when in raised position, and a combined cover and filling funnel for said drum, said cover comprising a plurality of radially disposed flaps, each flap being hingedly mounted along an outer edge on the upper edge of said sidewall and projecting radially inwardly of said sidewall, said flaps when in horizontal position with adjacent side edges overlapping providing a substantially closed cover for said drum, said flaps being movable from said horizontal position downwardly to an inclined position of the order of forty to sixty degrees to form a filling funnel for said drum, the side edges of one flap underlying the side edges of adjacent flaps, and means connected to said one flap for moving the same between horizontal and inclined position, said adjacent flaps by reason of the overlapping engagement with said one flap moving therewith, said flaps also being movable from said inclined position upon movement of said peripheral wall into engagement with said flaps.
